PARLOR STOVE.

No. 16,649.

Patented Apr. 20, 1886.

Fig. 2.

UNITED STATES PATENT OFFICE.

GURDON G. WOLFE AND AUGUST LISEWSKI, OF TROY, NEW YORK, ASSIGNORS TO THE FULLER & WARREN COMPANY, OF SAME PLACE.

DESIGN FOR A PARLOR-STOVE.

SPECIFICATION forming part of Design No. 16,649, dated April 20, 1886.

Application filed June 1, 1885. Serial No. 167,351. Term of patent 7 years.

To all whom it may concern:

Be it known that we, GURDON G. WOLFE and AUGUST LISEWSKI, both of the city of Troy, county of Rensselaer, and State of New York, have jointly invented and produced a new Design for Parlor-Stoves, of which the following is a specification.

Our design relates to the ornamentation of parlor-stoves, as is shown in the accompanying two plates of photographs, forming a part of this specification, that one of said photographs designated as Figure 1 showing a view of one side, and that designated as Fig. 2 illustrating a combined front and side view, of a stove containing our design.

The form of the stove to which our design is shown as applied is elliptical. The top of the stove, T, is made to overhang the body of the stove proper, and it is divided horizontally into the dome part T² and the molded part T³. The dome part of the top is ornamented at its base with a vertically fluted or milled ring of beveled band-molding, t', and next above the latter on the dome-face a ring 25 of scallops, t', having between each two of them the leaf-and-stem ornaments t². Upon the dome, above the scallops, there is a radiate ornament, t³, within the center of which the urn V is arranged when used. The compound 30 molding T³ on the stove-top, below the dome, is composed of a ring of band-molding on the overhanging edge t² an inwardly and upwardly inclined ring of milled band, t³, and a fillet, t⁴.

The form of the top, independent of the 35 ornamentations upon it, being made the subject of another application, is disclaimed herein.

The front of the stove, G, is divided from the sides or ends by means of the relief-pilasters P, which, considered alone and apart from the 40 combination in which used, are an old feature of ornamentation. These pilasters are made with molded plinths p' and mitered caps p², with intermediate flutings, p³, and scale ornamentation p⁴.

45 The stove-body is ornamented at its top, immediately beneath the top proper, with a figured and filleted molding in cymantum, b', and an ogee molding, b². The door D', arranged on the body near the top of the latter, has 50 four upper panes, d' d' d' d', three middle panes, d² d² d², and two lower panes, d³ d³, the upper

and lower panes of the door of each having about half the vertical depth of the middle panes. Two horizontal sash-bars, d⁴ d⁴, divide the upper and lower panes from the middle ones within the door-frame d⁵. The upper panes have radiate figures on each of the three stiles centrally placed therein, with intermediately-arranged rosettes, as indicated at d⁶. The lower panes of said door D' are two in 60 number, and these are divided by a central stile, with each of the panes containing two X-form figures arranged side by side within the panes, as indicated at d⁷. The center one of the middle panes d² is made with two reversing C-formed figures as interstiles, and the corners of the two panes d² d² at the sides of the center pane have rounded corners.

The letter M designates an ornamental figure arranged on the stove-front immediately 70 beneath the door D'. This ornament is formed by composite molding m', having rectilinear position at the sides and top of the figure, with the corners of the molding, where intersecting, being notched and mitered, as indicated at m², 75 the said molding inclosing a panel, m³.

The letter m⁴ indicates a filleted figure arranged, in the main, within said panel m³, but overlapping the same at the top by means of the scrolls m⁵ and at the sides by means of the 80 lateral extensions of said figure m⁴. The corners of said inter-figure m⁴ are notched similarly to those of the panel m³; but the filleted edges of the figure m⁴, between the notched portions and where overlapping the panels m³, 85 at the sides, top, and bottom of the latter, are curved, as indicated at m⁶. Within this interiorly-arranged figure m⁴ there is an interior panel, m⁷, for displaying the trade name of the stove, and below the latter panel there is arranged the leaf-form cup figure m⁸.

The ash-pit door D² has three panes formed in its frame p'. These panes are indicated at p' p² p³, and shown as divided off from the frame by two vertical stiles, with the center 95 pane ornamented by two reversing C-form figures like those shown in the center pane of the door D', and with the corners of the end panes of the ash-pit door rounded out in the same manner as those of the said upper 100 door, D'.

Each of the stove-sides is ornamented with

an upper relief figure, A, and a lower relief figure, O. The upper figure has a raised and molded border, a' , producing a panel, a^2 . This raised border is arched in upward extension at the top, as indicated at a^3 , and each of the top corners is notched, as designated at a^4 . The bottom of this molded border a' is arched centrally to correspond with that of the top, as indicated at a^5 , and the corners are notched, as designated at a^6 . The center of this panel a^2 contains in relief the urn and flowers a^6 , the reversing side scrolls, a^7 a^8 , arranged with pendent beads a^9 , and flower festoons a^{10} . The lower figure, O, has a composite molding, o' , inclosing a panel, o^2 . This molding o' is notched at all of its corners, as indicated at o^3 , the top of the molding being rounded out, as indicated at o^4 . Within the panel o^2 there is arranged the foliated harp-form scroll figure o^5 , with the central foliated ornament, o^6 .

25 The letter C designates a relief rosette figure arranged between the two reversingly curved or arched portions in the bottom of the figure A and the top of the figure O.

25 The rearward extension of the stove I is at each side ornamented with the lateral intaglio flutings f' and the shorter lateral relief flutings f^2 , and the base of the extension is molded and filleted, as indicated at f^3 .

30 The sides of the stove-base are ornamented with a figure, N, composed of the rectilinear molding n' , the panel n^2 , inclosed by the said molding, and the reversing vine and foliated relief scroll figures n^3 .

35 The feet of the stove, as designated at H, have a slight ogee curve on their outer face, and they are exteriorly ornamented with Y-form diverging and curved intaglio line h' , terminating in scrolls, the guttae or drop figures below said lines h^2 , the tarsal prominences h^3 , and the digital prominences and terminations h^4 .

Having thus described our invention, what we claim, and desire to secure by Letters Patent, is—

45 1. In a design for a stove, the configuration and ornamentation of the top T, having the dome part T^2 , ornamented with the scallops t' , the intermediate-arranged leaf- and -sprig figures t^2 , the central radiate figure, t^3 , and the vertically milled or fluted band-molding t^4 , with the compound molding T^5 below the dome part, composed of the members t^6 t^7 t^8 , as shown and described.

55 2. In a design for a stove, the configuration and ornamentation of the door D', consisting of the four upper panes, $d' d' d' d'$, having radiate ornaments on the sash-stiles, with intermediate rosettes, the three middle panes, $d' d' d'$, the center one of the latter having the reversing C-form interstiles, and the panes each

side of the center one of said middle panes having rounded interior corners, and the lower panes, $d' d'$, ornamented with X-form figures, as shown and described.

65

3. In a design for a stove, the ornamental figure M on the stove-front, and consisting of the compound-border m' , which incloses the panel m^2 , the border of which is notched and mitered at the corners, the interior name-plate panel, m^3 , within the said panel m^2 , said name-plate panel having a filleted border that is notched at the corners, and which at the top, bottom, and sides is to overlap the major panel m^2 , as shown and described.

75

4. The design for a stove, consisting of the ornamental figure A, having the molded border a' , the notched corners a^4 , the arches $d' d'$ at the top and bottom, and the intermediate reverse-scroll figures a^5 , the pendent flowers a^6 , and the bead festoons a^7 , the ornamental figure O, having notched corners o^3 and rounded-out top o^4 , and the harp-form scroll figure o^5 within the panel, and the rosette C between the figures A and O, substantially as described 80 and shown.

5. In a design for a stove, the configuration and ornamentation of panel N, having the border n' on the base, and inclosing the scroll, vine, and leaf figure n^3 , as shown and de- 90 scribed.

6. In a design for a stove, the ornamentation of the rearward extension I, consisting of the horizontal intaglio flutings f' , the horizontal relief-flutings f^2 , and the molding f^3 95 on the base of the extension, as shown and described.

7. In a design for the ornamentation of a stove, the feet H, having the bifurcating curved intaglio lines h' , terminating in scrolls on the exterior thereof, the drops h^2 below said lines, the tarsal prominences h^3 , and the digital terminations h^4 , as shown and described.

8. The design for a parlor-stove, embracing the top T, the front G, the door D', and the 105 ash-pit door D', all shaped and ornamented substantially as shown and described.

9. The design for a parlor-stove, embracing the top T, the front G, the door D', and the ash-pit door D', the relief figures A and O, 110 and the rosette C, and the figure N on the sides of the stove, the rear extension, I, and the feet H, all shaped and ornamented substantially as described and shown.

Signed at Troy, New York, this 10th day of 115 January, 1885, and in the presence of the two witnesses whose names are hereto written.

GURDON G. WOLFE.
AUGUST LISEWSKI.
